The ornamental design for a body orifice device, as shown
and described.

DESCRIPTION

FIG. 1 is a bottom right perspective view of a body orifice device.

FIG. 2 is a top perspective view thereof.

FIG. 3 is a right side view thereof.

FIG. 4 is a left side view thereof.

FIG. 5 is a top view thereof.

FIG. 6 is a bottom view thereof.

FIG. 7 is a front view thereof; and,

FIG. 8 is a rear view thereof.

The broken lines in the drawings are for illustrative purposes
only and form no part of the claimed design.
